ANGELO CESARE PARODI, OF JERSEY CITY HEIGHTS, NEW JERSEY.

EGG BOILER.

Application filed November 24, 1923. Serial No. 676,817.

To all whom it may concern:

Be it known that I, ANGELO CESARE PARODI, a citizen of the United States of America, and a resident of Jersey City Heights, in the county of Hudson and State of New Jersey, have invented a new and Improved Egg Boiler, of which the following is a description.

My invention relates to a known form of egg boiler in which the egg basket is adapted to be automatically lifted from the boiler after a lapse of a predetermined number of minutes for which the device is set.

In the known form of egg boiler to which my invention particularly relates certain defects lessen the practicability of the egg boiler and the general object of my invention is to overcome the defects referred to. One of the known defects is the mounting of the chain pulley. In the usual way of making the device a comparatively light casing is required to withstand the strains to which the pulley is subjected by rough usage as for example due to a sudden pull of the chain, thereby causing the weight to strike the pulley or parts adjacent thereto at the top of the egg boiler, the result being that the casing becomes distorted and the chain frequently displaced from the pulley.

My present invention overcomes the defect referred to and makes it impossible for rough usage to disrupt the assemblage and it serves to insure a proper guiding of the chain at all times.

A further defect in the known form of egg boiler in question heretofore made is due to the fact that steam rising from the boiler and contacting with the box containing the clock work assemblage causes expansion of the box and permits steam to enter with the result that the mechanism in the box becomes rusted. I provide an improved form of box the expansion of which will not permit steam to enter to the interior of the box.

Again, in the egg boiler referred to as usually made, a bridge piece is secured to the frame or casing in which bridge piece the gage pinion is located. The bridge piece and the coacting parts in the assemblage as usually made involve a large number of parts held together with small screws and the arrangement does not permit the pinion gage to be well lubricated nor does

the construction enable the parts to resist rough handling. I overcome the defects referred to by an improved bridge piece.

Again, in the egg boiler in question as usually made the means to lubricate the shaft of the ratchet pinion leaves much to be desired and my invention includes a means to overcome the defects by providing a construction greatly simplified and more effective in permitting the lubrication of the shaft of the ratchet pinion.

Reference is to be had to the accompanying drawings forming a part of this specification, it being understood that the drawings are merely illustrative of one example of the invention.

Figure 1 is a perspective view of an egg boiler generally of known form in which my improvements are embodied;

Figure 2 is a perspective view on an enlarged scale of the upper end of the egg boiler showing the pulley mount separated from the casing;

Figure 3 is a front view of the clock work box with the cover removed;

Figure 4 is a detail through the bridge piece and a portion of the clock train as indicated by the line 4-4, Figure 3;

Figure 5 is a perspective view of the bridge piece for the gage pinion;

Figure 6 is a horizontal section on the line 6-6, Figure 3;

Figure 7 is a horizontal section on the line 7-7 Figure 1;

Figure 8 is an enlarged section on the line 8-8, Figure 6.

The numeral 10 indicates a tubular standard or casing; 11, the clockwork box; 12, the egg basket having a rod 13 adapted to be lifted by an upward movement of the chain 14 which in practice is actuated by the dropping of a weight (not shown) in the standard 10. The dropping of the weight is controlled by clockwork mechanism according to the position of the setting slide 15 in a well known manner. The parts referred to are well known as features of the egg boiler to which the invention pertains and need no further description here.

In the operation of the egg boiler the steam rising from the vessel A into which the egg basket 12 is lowered heats the clockwork box 11 and in the expansion of the

box under the heat of the steam, the bottom of the box and the front 18 thereof separate leaving an inlet for the steam at the joint between the bottom and cover. To over-
5 come the objection referred to I form bottom 16 with a front lip 17 extending beneath and flush with the cover 18 so that there is no direct opening for the steam to pass into the box. The lip 17 referred to is
10 best shown in Figure 7.

The defective pulley or sheave assemblage in the egg boiler to which the invention pertains is remedied in my improvements as follows: Instead of the pulley pin being
15 passed through the sides of the casing or standard 10 leaving said sides to withstand the strains I provide cheeks 20 between which the pulley 19 is snugly accommodated with just sufficient clearance to revolve.
20 Said cheeks 20 are depending from the top plate 21 of the pulley mount and possesses rigidity to effectively withstand any strains exerted on the pulley. The pulley pin 22 projects beyond the cheeks 20 at each side
25 so as to abut against the inner surface of the sides of the casing or standard 10, the pin being thus held against longitudinal displacement without straining said casing. The cheeks 20 are formed with thickened
30 portions or lateral bosses 120 and a transverse pin hole 23 is produced through the bosses 120 and cheeks 20 beneath the top plate 21 so that a pin can be passed through the hole 20 and through the registering
35 holes 24 through the sides of the casing 10 as part of the means for securing the pulley mount in said casing. In front of the casing 10 a vertical opening 25 is formed into which the cheeks 20 extend to project be-
40 yond the front of the casing, there being a complementary slot 26 extending from the bottom of the opening 25 to afford clearance for the pulley 19. At the back of the top plate 21 is a depending flange 27 which is
45 formed with screw holes, there being registering holes 28 in the back of the case 10 so as to receive fastening screws for securing the flange 27 to said back of the casing. The numeral 28 indicates the usual lug on
50 the pulley mount formed with a tooth 29 to engage the teeth 31 on the setting bar 15. The numeral 30 indicates a slot in the pulley mount in which the setting bar 15 has guided movement.
55 The numeral 32 indicates the bridge piece fastened by screws 33 to the back of the clockwork box 11, the screws taking into tapped holes 34 in said bridge piece. The bridge piece supports the shaft 35 of the
60 gage pinion 36 and in the usual construction the assemblage involving the bridge 32 and pinion 36 includes a number of small parts held together by screws, the parts being liable to disarrangement and looseness.
65 I form a slot 37 for that pinion of the clock-

work engaging the gage pinion 36 and I provide a washer 38 on the pinion shaft 35, said washer being accommodated in a recess 39 in the bridge 32. After the washer 38 is placed in the recess 39 the opposite edge 70 portions 40 of the wall of said recess are indented or upset to retain the washer 38 in position.

In Figure 6 the numeral 41 indicates an extension block suitably secured as by a 75 screw or screws 42 to the back of the clock-work box 11, said extension forming a bearing for the shaft 43 of the ratchet pinion 44 of the clockwork. A lubricating means for the shaft 43 is defective in the usual construction of the egg boiler to which the invention relates and the construction shown in Figures 6 and 8 provides an effective lubrication. The bushing 45 fitted on the shaft 43 extends partially into a recess 46 leaving an annular channel 47 for the lubricant to which channel an oil hole 48 leads downwardly. An opening 49 is formed in a wall of the standard or casing 10 through which a nozzle of an oil can may be inserted 80 supplying oil to the oil hole 48.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims. 95

Having thus described my invention, I 100 claim:

1. In an egg boiler of the type including a boiling vessel, and a basket to be positioned in said vessel or lifted therefrom as well as having clockwork controlling the 105 lifting of the basket and disposed in the vertical plane of the boiling vessel; a clock-work box having a front cover and a bottom member, said bottom member formed with a lip overlapping and extending beneath the edge of said cover, to prevent the direct entrance of steam when the box expands when heated by the steam from the boiling vessel. 110

2. In an egg boiler having an egg basket and lifting means for said egg basket comprising a lift chain; a tubular standard, a pulley mount on said standard at the top, cheeks on the pulley mount in close relation to the pulley, and a pulley pin passing through the 115 cheeks and pulley and supported in the cheeks independently of said standard. 120

3. In an egg boiler having an egg basket and lifting means for said egg basket comprising a lift chain; a tubular standard, a pulley mount on said standard at the top, cheeks on the pulley mount in close relation to the pulley, and a pulley pin passing through the cheeks and pulley and supported in the cheeks independently of said 125 130

standard, said pin projecting beyond said cheeks and lying at its ends in close relation to opposite sides of the standard.

4. In an egg boiler of the class described having a basket, and lift means for the basket, clockwork controlling the lift means, and a bridge piece mounting the spindle of one of the pinions of the clockwork, said bridge piece formed with a recess about said spindle, and a washer on the spindle in said recess, the material of the bridge piece being upset over the outer face of the washer to retain the same in position.

5. In an egg boiler having a standard, an

egg basket, lift means for the basket, and a clock train controlling the lift means, a box enclosing the clock train, and a block secured to the back of said box and forming a rigid extension thereof, together with a pinion shaft turning in said block, said block having a countersunk recess about the shaft, and a bushing on said shaft at said recess and terminating short of the inner end of said recess, thereby providing an oil chamber at the inner end of the bushing, said block having an oil inlet hole leading to said oil chamber.

ANGELO CESARE PARODI.
